ACCOUNTING MACHINE

Charles J. Goedale and Harry B. Marvin, Schenectady, N. Y., assignors to General Electric Company, a corporation of New York

Application March 22, 1945, Serial No. 584,148

21 Claims. (Cl. 235—61)

1

This invention relates to accounting machines, and more particularly to an electrically operated accounting machine, and it has for an object the provision of a simple, reliable, and improved machine of this character.

An object of the invention is to provide an improved accumulator mechanism for performing additions and subtractions.

A further object of the invention is to control the counting movements of the accumulator counting elements by means of electric valve apparatus.

A further object of the invention is to control the electric valve apparatus by means of timing circuits having time constants corresponding to the digit numerals from 1 to 9 inclusive in order to effect movements of the counting elements of the accumulators corresponding to the digit numerals.

A further object is to provide adding and subtracting apparatus of the above character including means for effecting carryovers, setting up negative totals, and for clearing the accumulator.

In carrying the invention into effect in one form thereof, an accumulator is provided with a constant speed driving means and with a stationary holding member. Each of the orders of the accumulator has a counting element which is normally held in engagement with the stationary member. The engagement of the counting element with the driving means and the reengagement of the counting element with the stationary member is controlled by suitable electric valve means constituting a part of each order. The counting movement of the counting elements is controlled by controlling the time which the counting element is in engagement with the constant speed driving means. This is accomplished by means of a plurality of timing circuits having time constants corresponding to the digit numerals.

For a better and more complete understanding of the invention, reference should now be had to the following specification and to the accompanying drawings of which Fig. 1 is an exterior view in perspective of a preferred form of a device embodying the invention; Fig. 2 is a view in perspective of a portion of the keyboard and mechanism associated with the amount keys for making item entries and for selecting the timing circuits corresponding to the digit numerals of the item entries recorded; Fig. 3 is a view in elevation partly in section of two counting elements, the constant speed driving means, and the electromagnets for moving the counting element into

engagement with the driving means or with the stationary element; Fig. 4 is a view in perspective of a detail of the counting mechanism; Figs. 5a and 5b are simple, diagrammatic sketches of the electrical and electronic apparatus of the accumulator; Fig. 6 is a chart of characteristic curves which serve to facilitate an understanding of the operation of one portion of the electronic apparatus; and Fig. 7 is a fragmentary view illustrating the amount key lockout mechanism.

Referring now to the drawings, an accounting machine accumulator mechanism is mounted in a casing 1 of suitable construction. Although any suitable means may be provided for making item entries, a plurality of rows 2, 3, 4, and 5 of amount keys are illustrated for the purpose of simplicity. Beginning at the right-hand side, the rows 2, 3, and 4 belong to the units, tens and hundreds orders, respectively. The row 5 at the left-hand side of the longitudinal break belongs to the Nth order. For example, if the machine is to have nine columns the Nth column 5 would be the ninth column or the column belonging to the hundred millions order.

25 The accumulator is provided with a plurality of counting elements, one counting element for each order. These elements are preferably constructed in the form of wheels or disks. Two of these disks 6 and 7 are illustrated in Fig. 3. Although only two such disks are illustrated, it is to be understood that there is one counting disk for each order. They are all identical and the disk 7 is described as typical. It is made of a suitable magnetic material, e. g., a nickel iron alloy having approximately 60% iron and 40% nickel. The disk 7 is mounted for rotation with respect to the shaft 8 and to this end it is provided with a bearing sleeve 7a which is freely rotatable on and axially slidabile along the shaft 8. This sleeve is made of a suitable nonmagnetic material such as brass. The disk 7 is provided with a flange 7b upon which the digit numerals 0 to 9 inclusive are successively imprinted in the forward or positive direction as illustrated on the flange of the disk 6. As shown in Fig. 1, the counting disks are so arranged that the numerals on the flanges are located beneath the windows 9, 10, 11, and 12 in the casing.

For the purpose of effecting rotation of the 50 counting disks during a counting operation and for holding them against rotation at other times, a plurality of suitable means 13, 14, etc., one for each counting disk, are provided for normally holding the disk in engagement with a stationary member, and for effecting engagement of the disks

with a constant speed driving member during a counting operation. These means are illustrated as electromagnetic means, and since they are all identical, the electromagnetic means 14 is described as typical. It comprises two spaced-apart electromagnets having operating coils 14a and 14b which are wound on spools 14c and 14d respectively. These spools are secured to frames 14e and 14f by suitable fastening means. The frames 14e and 14f in turn are secured to supporting uprights 14g and 14h which are suitably secured to the bottom plate 15 of the machine.

The frame 14c is provided with a suitable bearing 16 in which the shaft 8 is journaled for rotation. The coil 14a is provided with a core member 14i which is secured to the shaft 8 for rotation therewith. The coil 14b is provided with a stationary core member 14j which is secured to the frame 14d. This stationary core member is provided with a centrally disposed circular opening through which the sleeve 7a and shaft 8 project. The rotatable core 14i is provided with a ring 17 which is made of a suitable nonmagnetic material such as brass and is suitably secured to the core member as by swaging. Similarly, the stationary core member 14j is provided with a ring 18 which is made of brass or other suitable nonmagnetic material and is secured to the core by swaging or other means. An enlarged view of the ring 18 is illustrated in Fig. 4. This ring is provided with a plurality of indentations 18a which are pressed into the ring by a suitable forming die. As shown, the ring 18 has twenty of these indentations. However, it might have a different number of such indentations. For example, it might have ten indentations.

The disk 7 and the rotatable ring 17 are each provided with an equal number of similar indentations which are the counterparts of indentations 18a. The indentations of the disk together with the indentations of whichever of the rings the disk is in contact with constitute interengaging elements. The rings 17 and 18 and the disk 7 are so designed that when the indentations of the disk engage those of either ring the disk is separated from the corresponding magnet core 14i or 14j by a small airgap, e. g., .018 in. The disk 7 is illustrated in its normal position in engagement with the stationary ring 18. When the coil 14h is energized, the counting disk 7 is attracted and held in engagement with the stationary ring 18. Similarly, when the coil 14a is energized the counting disk 7 is attracted and held in engagement with the rotatable ring 17. The shaft 8 is driven at a constant speed by suitable constant speed driving means such as the single phase self-starting synchronous motor 19 to the drive shaft of which the shaft 8 is connected through suitable reduction gearing (not shown). As shown in the electrical diagram of Fig. 5b, the motor 19 is supplied from a suitable source of alternating voltage which is preferably a commercial 60 cycle source. It is represented in Fig. 5b by the two supply lines 20.

The motor 19 is preferably a 4-pole motor and the reduction gearing preferably has a ratio of 5:1. Thus the synchronous speed of the motor is 1800 R. P. M. and the speed of the shaft 8 is 360 R. P. M. This speed is equal to 36 mechanical degrees for each cycle of the alternating voltage of the source 20 or 6 revolutions per second. Thus the core 14i which is fixed to the shaft rotates at a speed of 6 revolutions per second. Since the digit numerals 0-9 are equally spaced

on the flange of the counting disk, these numerals are spaced 36 degrees apart. Consequently a rotation of the disk for a count of 1 requires that the disk be in engagement with the rotating ring 17 for $\frac{1}{60}$ second and a count of 9 requires an engagement of $\frac{9}{60}$ second.

A starting switch 21 serves to connect the motor 19 to the source and a reversing switch 22 controls the direction of rotation of the motor, thereby providing for adding or subtracting operations. In the position of the switch which is illustrated in Fig. 5b the motor operates in the adding direction. When the "subtract" key (Fig. 1) is depressed, the switch 22 is operated to the reverse position and the motor rotates in the reverse or subtract direction.

For the purpose of controlling the energization of the operating coils of the electromagnets which effect the alternate engagement of the counting disk of each order with the driving motor and the stationary holding member, suitable electric valve control means are provided. The electric valve control means for the units, tens and hundreds orders are shown in Figs. 5a and 5b within the dotted rectangles 23, 24, and 25 respectively. The electric valve control means for the Nth is shown within the rectangle 26. Since the electric valve control means for all order sections are substantially identical, the electric valve control means for the tens order is described as typical of all. In describing this control means for the tens order section it may be assumed that the disk 7 of Fig. 3 is the counting element for the tens order. The energization of the operating coils 14a and 14b of the electromagnet 14 is controlled by electric valves 27 and 28 respectively under the control of a plurality of timing circuits shown within the dotted rectangle 29.

Although the electric valves 27 and 28 may be of any suitable type, they are preferably thyratrons. These thyratrons are provided with anodes 27a and 28a, cathodes 27b and 28b, control grids 27c and 28c, and shield grids 27d and 28d, respectively. A small amount of mercury vapor or an inert gas such as argon is contained within the envelope. The presence of gas or mercury vapor converts the usual pure electronic discharge into an arc stream. The output circuits of these thyratrons, i. e., the anode cathode circuits, are connected across a source of direct voltage which is represented by the positive and the negative buses 30 and 31. The operating coils 14a and 14b of the electromagnets are connected in the output circuits of electric valves 27 and 28 respectively in series with voltage drop resistors 33 and 34 respectively. When the valve 27 is conducting, operating coil 14a is energized and the disk 7 is attracted into engagement with the rotatable ring 17. Similarly, when the valve 28 is conducting, operating coil 14b is energized and the disk is attracted into engagement with the stationary ring 18. Consequently, the valve 27 and the operating coil 14a are referred to as the "run" valve and the "run" operating coil respectively, and the valve 28 and the operating coil 14b are referred to as the "standby" valve and the "standby" operating coil, respectively.

A characteristic of electric valves such as the thyratrons 27 and 28 is that the valve may be rendered conducting only by simultaneously making the voltage of both the control grid and the shield grid less negative or more positive than a predetermined critical value.

In order to maintain the valve 27 normally nonconducting the control grid 27c is connected by means of a conductor 35 to a point of negative voltage 36a on a voltage divider comprising resistors 36, 37, and 38 connected in series relationship with each other. The upper terminal of the voltage divider is connected to the negative bus 31. A direct voltage is supplied to this voltage divider by means of a rectifier 39 with which the divider is connected in series across the alternating voltage source 20. The rectifier circuit is traced from the upper terminal of the source 20 by conductor 40 to the negative bus 31, divider resistors 36, 37, and 38, rectifier valve 39, to the opposite terminal of source 20. As a result of this connection, the voltage of point 36a of the divider is negative with respect to the negative bus 31 by the amount of the voltage drop across resistor 36.

The conductor 35 which is connected to the negative point 36a of the divider and to which the control grid 27c is connected also serves as a common conductor for supplying a negative bias voltage to the control grids of the run valves 41, 42 and 43 of the units, hundreds and Nth order respectively.

Another characteristic of thyratron valves is that once the valve has become conducting, the grid is powerless to terminate the current flow in the output circuit. This can only be done by means external to the valve itself, i. e., either by interrupting the output circuit or reducing the anode voltage to zero, or to a value which is negative with respect to the voltage of the cathode. In order that the counting disk 7 may be engaged with either the rotating ring 17 during a counting operation or with the stationary ring 18 when the counting operation is terminated, it must not be subject to simultaneous opposite attracting forces. Consequently, when either valve 27 or 28 becomes conducting the other valve must be rendered nonconducting. In order to provide for this alternate conduction of the valves 27 and 28 a commutating capacitor 44 is connected between the anodes 27a and 28a of the two valves. This capacitor operates in the following manner. Assume that the standby valve 28 is conducting and that the run valve 27 is nonconducting. At this instant the voltage of the anode 27a is the voltage of the positive terminal of the source 30. The voltage of the anode 28a is positive with respect to its cathode only by the amount of the drop across the valve 28 which is a relatively small amount. Further assume that the valve 27 is rendered conducting by simultaneously making the voltage of the grids 27c and 27d less negative than the critical firing value. The valve 27 becomes conducting and a large voltage drop is produced across the operating coil 14a and the solenoid 45 and the resistor 33 in the anode circuit. As a result, the voltage of the anode 27a is suddenly decreased from a high value almost to the voltage of the negative terminal 31 of the source. The voltage across the capacitor 44 can change only as rapidly as the capacitor discharges and charges and since the capacitor cannot discharge and charge instantaneously, the voltage of the anode 28a is instantaneously decreased the same amount that the voltage of the anode 27a is decreased. Consequently the voltage of anode 28a is instantaneously decreased by a large amount which is sufficient to make it negative with respect to the cathode, thereby extinguishing conduction of run valve 27. As the capacitor 44 charges, the voltage of the anode 28a of the standby valve

increases to the voltage of the positive terminal 30 of the source.

If the standby valve is fired by simultaneously making the voltages 28c and 28d less negative than the critical firing value, the capacitor 44 operates in the same manner as described in the foregoing to extinguish conduction in the run valve. Thus the commutating capacitor 44 constitutes a means for terminating conduction in either valve in response to initiation of conduction in the other valve.

For the purpose of maintaining the counting disk 7 in engagement with the rotating ring 17 for intervals of time which will effect amounts of rotation of the disk which correspond to the digit numerals, it is necessary to maintain the run valve 27 conducting and the standby valve 28 nonconducting for such periods of time. This is accomplished by means of a plurality of timing circuits having time constants which correspond to the digit numerals for preventing reestablishment of conduction in the standby valve for intervals of time corresponding to the digit numerals. These timing circuits are formed by the selective connection of the capacitor 46 in series with resistors 29a to 29i inclusive within the dotted rectangle 29.

The capacitor 46 is connected between the anode 27a of the run valve and the control grid 30 28c of the standby valve. When the run valve becomes conducting the capacitor 46 operates to make the voltage of grid 28c very negative with respect to the voltage of the cathode. This operation is similar to the operation of the commutating valve 44 described in the foregoing.

This selective connection of the resistors 29a to 29i inclusive is accomplished by means of the plurality of amount keys which are comprised in the row 3 of Fig. 1. There are nine of these 40 amount keys, one for each digit of 1-9. Operatively associated with these amount keys is a corresponding plurality of switching devices 29j to 29r inclusive. The switch 29j which is typical of all the switches associated with the amount keys 45 is provided with a pair of stationary contacts and with a movable contact which is normally separated from the stationary contact. The movable contact is provided with a button 29', Fig. 7, which normally projects into a slot on a cam 29'' which is secured to the stem of the associated amount key. When the one amount key is depressed, the cam moves the button into the switch casing to cause the movable contact member to bridge the stationary contact members, thereby to complete the connection of the resistor 29a in circuit with the capacitor 46. Each of the amount keys is provided with a similar cam which actuates the button of its associated switch.

60 The resistor 29a has an ohmic value such that when connected in circuit with the capacitor 46 the time constant of the circuit is of the order of $1/60$ second. However, this resistance value is not critical. It may vary 20 per cent. Thus, if the run valve is rendered conducting and the timing circuit through switch 29j is simultaneously completed, the voltage of the control grid of the standby valve is maintained below the critical firing value for slightly less than $1/60$ second.

65 The voltage of the shield grid is maintained below the critical firing value for $1/60$ second, since the voltage of both grids must be above the critical value to render the standby valve conducting. In other words, the control grid circuit must restore the grid voltage of the standby valve to

firing value within the desired $1/60$ second so that the shield grid may fire the valve after exactly $1/60$ second. Consequently, the counting disk is maintained in engagement with the rotating ring 17 for $1/60$ second and is rotated through 36 degrees for a count of 1. The resistors associated with the amount keys have resistances which when connected in circuit with capacitor 16 result in time constants which produce rotation of the counting disk and numerical counts as shown in the following table:

Amount Key	Resistor	Resistance, ohms	Time, Sec.	Degrees Rotation of Disk	Count
1	29j	59,000	.360	36	1
2	29k	87,000	.260	72	2
3	29l	130,000	.260	108	3
4	29m	160,000	.260	144	4
5	29n	193,000	.260	180	5
6	29o	235,000	.260	216	6
7	29p	279,000	.260	252	7
8	29q	320,000	.260	288	8
9	29r	369,000	.260	324	9

The foregoing table is merely illustrative of one set of values which produces satisfactory results with given circuit constants.

The constructional details of the mounting and interlocking of the amount keys of row 3 are illustrated in Fig. 2. These amount keys are slidably mounted in a supporting upright 48 which is suitably secured to the frame of the machine. In Fig. 2 a portion of this upright 48 is broken away to reveal the detailed construction of the 1 amount key which is typical of all. This amount key is biased to its uppermost position by means of a tension spring 49 which is connected between the upright 48 and a pin which is secured to the stem of the key.

Suitable interlocking means are provided for preventing a second amount key in the tens order from being depressed until an earlier depressed key has been released and returned to its uppermost position. These interlocking means comprise a bar 50 which is slidably mounted in a groove in the upright 48, a bellcrank 51 for each key, an upper pin 52a and a lower pin 52b on the stem of each key, a latch 50a and a pin 50b for each key mounted on the bar 50. The bellcrank is pivotally secured to the upright 48 and its horizontal arm is bifurcated to provide a slot in which the pin 52b slides. When an amount key, e.g. the amount 2 key, is depressed the resulting downward movement of pin 52b rotates the bellcrank 51 in a counterclockwise direction. After an amount of rotation which is sufficient to permit the upper pin 52a to descend to a point below the level of the latch 50a, the upright arm of the bellcrank 51 engages the pin 50b and moves the rod 50 to the left against the tension of a spring 53. In moving to the left, the rod 50 moves the latch 50a beneath the top pins 52a of the undepressed keys in the tens order. Additional interlocking means are provided for preventing two adjacent keys in the same column from being simultaneously depressed. These interlocking means are illustrated in Fig. 7 in which the switches 29j, 29k, and 29l of the tens order are shown together with the 1, 2, and 3 amount keys by means of which they are operated respectively. As shown, the actuating button of each switch is mounted on a rod which projects entirely through the switch casing. Similarly, the stem of each amount key is provided with a square slot which cooperates

with the rod of the switch which is actuated by the next higher amount key. Thus, when the 2 amount key is depressed, the rod of the switch 29k is forced into the slot on the stem of the 1 amount key, thereby to prevent the latter from being depressed. Simultaneously, the slot on the stem of the 2 amount key is moved below the level of the rod of switch 29l with the result that switch 29l cannot be operated and the 3 amount key cannot be depressed.

For the purpose of initiating conduction of the run valve 27 in response to depression of an amount key, switching means comprising three switches 54, 55, and 56 are provided as shown in

Fig. 2. Each of these switches is similar in construction to the switch 29. The actuating button of each switch is provided with a rod which passes entirely through the switch and projects beyond its casing on the opposite side. The switches 54 and 55 are provided with normally closed contacts 54a and 55a respectively and the switch 56 is provided with normally closed contacts 56a and normally open contacts 56b as illustrated in Fig. 5b. As shown in Fig. 2, the switches 54, 55, and 56 are mounted on the upright 48 and are arranged in a vertical bank with the projecting rod of one resting against the button of the switch which is immediately beneath it.

The rod 58 is provided with a cam 50c which depresses the button of the switch 54 when the rod moves to the left, thereby opening the normally closed contacts 54a, 55a, and 56a and closing the normally open contacts 56b.

A starting capacitor 57 is connected from the negative conductor 35 through normally closed contacts 56a to an intermediate point of positive voltage on a voltage divider which comprises resistors 58 and 59 connected in series across the direct voltage source 30, 31. The capacitor 57 is normally charged with the full voltage between the points 58a and 36a across its terminals. When the starting switch is operated to open contact 56a and close contact 56b, the positive terminal of the capacitor 57 is connected to the control grid 27c of the run valve and the voltage of the capacitor is applied across a resistor 60 which is connected between the grid and the negative potential resistor 35. As a result, the voltage of the control grid 27c is raised above the critical firing value. The resistance of resistor 60 is of the order of a megohm. Consequently, the rate of discharge of capacitor 57 is very low and the high positive voltage is maintained on the control grid for a period slightly in excess of $1/60$ second.

As stated in the foregoing, conduction in the valve 27 can only be initiated by simultaneously raising the voltages of both grids 27c and 27d above the critical firing value. In order that the counting disk shall register the correct count it is necessary that the run valve be fired only in predetermined positions of the rotating ring 17 in which the teeth of the disk can mesh accurately with the teeth of the ring, irrespective of the relative positions of the teeth of the ring and the counting disk at the instant of depressing an amount key. It is also necessary that the standby valve be fired at the correct instant at the end of the timing interval to effect accurate meshing of the teeth of the counting disk with the teeth of the stationary ring 18. To accomplish this, means are provided for raising the voltage of the shield grids 27d and 28d of the run and standby valves above the critical values in timed relation to the alternating voltage wave of

the source 20 from which the synchronous driving motor is supplied. For this purpose, an electric valve blocking oscillator is provided. This blocking oscillator is illustrated within the dotted rectangle 61 in Fig. 5b. This blocking oscillator comprises a high vacuum electric valve 62 having its anode cathode or output circuit connected across the alternating voltage source 20. The cathode is connected to the side of the source 20 to which the cathodes of the run and standby valves are connected through conductor 40. The primary winding 63a of a transformer 63 and two resistors 64 and 65 are included in the anode cathode circuit. A resistor 66 and a blocking capacitor 67 are connected across the secondary winding 63b of the transformer. The voltage supplied from the source 20 to the anode cathode circuit of the oscillator valve 62 is represented in Fig. 6 by the sinusoidal curve 68.

This oscillator 61 has anode current, grid voltage and anode voltage characteristics which are represented by the curves 69, 70 and 71, respectively. The anode voltage is a steeply peaked periodic voltage whose maximums occur once during each positive half cycle of the alternating voltage impressed on the anode of the oscillator valve. This voltage is transmitted through a capacitor 72 and conductors 73 and 74 to the shield grids 27d and 28d of the run and standby valves 27 and 28. The grids are connected through a resistor 75 to a point 37a of negative voltage on the voltage divider 36, 37, 38 and are thus negatively biased below the critical firing value as illustrated by the horizontal portions of the curve 76 in Fig. 6 which represents the voltage of the timing voltage wave. However, the increase in voltage which is transmitted through capacitor 72 abruptly increases the voltage of the shield grids 27d and 28d to the critical value.

The result is that the voltage of the grids 27d and 28d equals or exceeds the critical firing value during a brief interval in each positive half cycle of the alternating voltage of the source 20. These intervals are represented by the peak portions 76a of the curve 76 above the zero axis. They are of approximately .001 second duration and are separated by equal intervals of time of $1/60$ second. Thus, the electric valves 27 and 28 can be fired only during these brief intervals which are accurately timed with respect to the positions of the indentations of the rotating ring 17. The position of the rotating ring on the motor shaft is initially adjusted so that when the run valve is fired during one of these intervals the counting disk is attracted into accurate mesh with the rotating ring. This accurate meshing results irrespective of the position of the rotating ring at the instant of depressing an amount key.

The voltage divider 36, 37, 38 and rectifier 39 provide the control grid bias voltages for the run and standby valves of all order sections of the accumulator. Similarly, the blocking oscillator provides periodic triggering voltages of brief duration for the run and standby tubes of all order sections of the accumulator.

The operation to record an amount in any order will be understood from the following description. Let it be assumed that it is desired to record the count of 8 on the counting disk 7 of the tens order. It is also assumed that the disk is in the home or zero position, i. e. the numeral 0 appears in the window 10 in Fig. 1. The control grid 28c of the standby valve of the tens order section is connected through a resistor 77 to the positive conductor 30. The resistor 77

has a resistance of the order of one megohm. Since the grid 28c is connected to the positive side of the source 30, the standby valve 28 will be fired by the first peak of the triggering voltage which is supplied from the oscillator 61 to the shield grid 28d following the closing of the line switch 78 to connect the machine to the alternating voltage source 20. To record the count of 8, the 8 amount key in the tens order is depressed to close the switch contacts 29g, thereby to complete a timing circuit for the capacitor 46 through the timing resistor 29h. The depression of the amount key 8 moves the rod 50 (Fig. 2) to the left, thereby opening the normally closed contacts 54a, 55a and 56a and closing the normally open contacts 56b. As a result, the charge of the condenser 57 is applied to the control grid 27c of the run valve, and on the succeeding peak of the triggering voltage which is supplied from the oscillator 61 to the shield grid 27d the run valve 27 is fired. Responsive to the firing of the run valve, the commutating condenser 44 extinguishes conduction in the standby valve thereby deenergizing the standby operating coil 14b, and the timing capacitor 46 reduces the voltage on the control grid 28c of the standby valve below the vertical firing value. Simultaneously, the operating coil 14a is energized and attracts the counting disk 7 into engagement with the rotating ring 17. The disk is rotated in a positive direction. The commutating capacitor 44 recharges rapidly after the beginning of conduction in the run valve. However, the voltage of the control grid 28c of the standby valve remains below the critical firing value for a period of time determined by the time constant of the timing circuit comprising the capacitor 46 and the resistors 29h and 77. As set forth in the foregoing table, this period is $\frac{1}{60}$ second. Slightly prior to the expiration of this time interval, the voltage of the control grid 28c reaches the critical firing value. Exactly $\frac{1}{60}$ second following the initiation of the run valve a peak of triggering voltage is supplied from the oscillator 61 to the shield grid 28d. Consequently, the voltages of both grids 28c and 28d are simultaneously above the critical firing value and the standby valve 28 is fired. In response to the initiation of conduction in the standby valve, the commutating capacitor 44 extinguishes conduction in the run valve, thereby deenergizing the operating coil 14a. The conduction in the standby valve energizes the operating coil 14b, thereby attracting the counting disk 7 into engagement with the stationary ring 18 to terminate its rotation. In the period of $\frac{1}{60}$ second during which the counting disk was in engagement with the rotating disk it was rotated through an angle of 288 degrees. As a result, the digit numeral 8 appears in the window 10.

Whenever the run operating coil 14a is energized, the solenoid 45 which is connected in series with the run operating coil is also energized. As illustrated in Fig. 2, the solenoid 45 is secured to the upright 48 and its plunger 45a is connected to the rod 50. The energization of the solenoid 45 attracts its plunger in a direction to move it to the left. Consequently, the contacts 29g of the timing circuit are maintained closed until the standby valve is fired again and conduction in the run valve is extinguished at the end of the time interval required for the count corresponding to the depressed key. Thus, an accurate count is insured regardless of the length of time which the operator maintains the key depressed.

If it is desired to subtract an amount from the

total of the previously registered amounts in the accumulator, the subtract key in Fig. 1 is first depressed, thereby to operate the reversing switch 22 to its lowermost position to provide for rotation of the synchronous driving motor 19 in the reverse or negative direction. If it is desired to subtract 8 from what has been previously recorded above in the accumulator, i. e., 80, the 2 amount key in the tens order is again depressed. As a result, the operation described in the foregoing is repeated with the exception that the disk is rotated in the opposite direction. As a result, the disk is brought to rest after the rotation of -288 degrees with the numeral 0 appearing in the window 10.

In order to provide for effecting carryovers from one order to the next higher order, each order section is provided with a carryover switch which is actuated by the counting disk of the next lower order. Thus, the units, tens, and hundreds order sections are provided with carryover switches 79, 80 and 81, respectively. Also, the Nth order section is provided with a carryover switch 82, the purpose of which is to provide for the "fugitive one" which enters into calculations in which negative balances are shown as 9's complements.

The carryover switches 79, 80, etc. are identical with the switch 29j (Fig. 2). As shown in Fig. 5b, the carryover switch 80 for the tens order is provided with normally closed contacts 80a and normally open contacts 80b. As shown in Fig. 3, the carryover switches are mounted beneath the electromagnets which control the movements of the counting disks. The means for actuating the carryover switch 80 of the tens order is described as typical. The upright 14h is provided with bosses having aligned holes in which a push rod 83 is slidably mounted. The lower end of this push rod rests upon the actuating button 80c of the carryover switch. The bearing sleeve 7a is provided at its right-hand extremity with a small cam 7c which is arranged in such a position with respect to the digit numerals on the flange that it engages the top of the push rod 83 midway between the count of 9 and 0. That is, the cam engages the push rod and closes the contacts of the switch 80 when a point appears in the window is halfway between the 9 and 0 digit numerals.

Cooperating with the carryover keys are carryover capacitors 84, 85, 86 and 87 for the units, tens, hundreds, and N^{th} order sections, respectively.

These capacitors are normally discharged. For example, the carryover capacitor 85 is normally connected across the one megohm resistor 88 of the hundreds order. The circuit is traced from the lower plate of the capacitor 85 through the normally closed contacts 89a of the clear switch, by conductor 90, normally closed contacts 80a of the carryover switch, conductor 91, normally closed contacts 89b of the clear switch, normally closed contacts 92b of the starting switch of the hundreds order, resistor 88 and then by conductor 35 to the upper plate of the capacitor 85.

The manner in which carryovers are effected will be understood from considering the following problem in addition. It is assumed that the amount 287 is recorded on the counting disks, i. e., the units counting disk reads 7, the tens counting disk reads 8, the hundreds counting disk reads 2 and the remaining counting disks up to and including the Nth disk read 0. To the previously recorded amount of 287 the amount 513 is

now to be added. The reversing switch 22 is in the upper position to provide for rotation of the shaft 8 in the positive direction. In response to the depression of the 5 amount key in the hundreds order the counting disk is advanced 180 degrees in the positive direction so that the digit numeral 7 appears in the window 11. The operation is identical with that described in the foregoing for recording a positive amount on a counting element. The depression of the 1 amount key in the tens column advances the counting disk 36 degrees in the positive direction so that the numeral 9 appears in the window 10. Similarly, the depression of the amount key 3 in the unit column advances the units counting disk 108 degrees in the positive direction so that the 0 appears in the window 9. During the passage of the units counting disk from the 9 to the 0 position the units carryover switch 79 is actuated to the lower position to open the normally closed contacts 79a and to close the normally open contacts 79b and immediately thereafter to permit the movable contact member to return to the uppermost position to open the normally open contact 79b and to close the normally closed contact 79a. During the brief interval in which the contacts 79b are closed, the lower plate of the capacitor 24 is connected to the positive terminal 39 of the source. The capacitor is charged with the full voltage between the terminal 39 and the negative voltage of the point 36a. When the normally closed contacts 79a are reclosed as a result of the carryover cam passing out of engagement with the actuating rod of the switch 79, the positively charged terminal of the capacitor 84 is connected to the control grid 21c of the run valve 27 of the tens order over a previously traced circuit. As a result, the run valve 27 is fired when the next succeeding peak of triggering voltage is supplied from the oscillator 61 of the shield grid 21d of the run valve. In a manner identical with that described in the foregoing, conduction is extinguished in the standby valve 28 and the tens order counting disk 7 is attracted into engagement with the rotating ring 17. The starting switch 54 is in its uppermost position since no amount key is now depressed. Consequently, the normally closed contacts 54a bridge the contacts 29j so that the count of 1 timing resistor 29a is connected in circuit with the timing capacitor 46. After an interval of time of $1/60$ second, the voltage of the control grid 28c of the standby valve reaches the critical firing value and an impulse of triggering voltage from the oscillator 61 is simultaneously supplied to the shield grid 28d. This results in firing the standby valve and extinguishing conduction in the run valve, thereby to attract the counting disk into engagement with the stationary ring 18. During the $1/60$ second interval in which the counting disk was in engagement with the rotating ring 17 it advanced 36 degrees in the positive direction so that the numeral 9 now appears in the window 10. In a similar manner, when the counting disk 7 of the tens order passes from the 9 to the 0 position, the cam 7c actuates the tens order carryover switch 80 with the result that the counting disk of the hundreds order is advanced 36 degrees so that the numeral 8 appears in the window 11. Thus, the correct sum 800 is registered on the counting disks.

To illustrate the operation of the carryovers during subtraction, assume that the amount 754 is registered on the counting elements and that the amount 589 is to be subtracted therefrom. The subtract key of Fig. 1 is depressed to operate

the switch 22 to its lower position to provide reverse rotation of the motor 19 and the shaft 8. The operator depresses the 5 amount key in the hundreds order, the 8 amount key in the tens order and the 9 amount key in the units order. In response to the depression of the 5 amount key in the hundreds order, the counting disk in the hundreds order is rotated 180 degrees in the reverse direction so that the digit numeral 2 appears in the window 11. In response to depression of the 8 amount key in the tens order the counting disk of the tens order is rotated 238 degrees in the reverse direction so that the numeral 7 appears in the window 10. As the counting disk 7 passes from the 0 to the 9 position in the reverse direction of rotation, the cam 7c actuates the carryover switch 80, thereby effecting a carryover into the hundreds order which is similar to that described in the foregoing example of carryovers in addition with the exception that the carryover is in the reverse direction owing to the reverse direction of shaft 8. Consequently, the counting disk of the hundreds order is rotated another 36 degrees in the reverse direction so that the digit numeral 1 appears in the hundreds order window 11. The depression of the 9 amount key in the units order effects a rotation of the units order counting disk 6 of 324 degrees in the reverse direction so that the numeral 5 appears in the window 9. In passing from the 0 to the 9 position, the units carryover switch 79 is operated to effect a carryover of 1 into the tens order. Owing to the reverse rotation of the shaft 8, this carryover is in the reverse direction. Thus, the tens order counting disk 7 is rotated another 36 degrees in the reverse direction so that the numeral 6 appears in the window 10. Thus, the amount 165 appears in the windows.

In order to illustrate the carryover from the Nth order to the units order to provide the "fugitive one" in calculations involving subtractions in which a negative balance results, it is assumed that the amount 150 is registered and that it is desired to subtract therefrom the larger amount 224. The numeral 0 appears in the Nth order window 12 and in all windows between the Nth order and hundredths order. The operator depresses the 2 amount key in the hundreds order, the 2 amount key in the tens order and the 4 amount key in the units order. In response to depression of the 2 amount key in the hundreds order, the counting disk is rotated 72 degrees in the reverse direction so that the digit numeral 9 appears in the window 11. In passing from the 0 position to the 9 position, the carryover switch 81 of the hundreds order is actuated and this effects a carryover of 1 in the next higher order which in this case is assumed to be the Nth order. As a result, the counting disk of the Nth order is rotated 36 degrees in the reverse direction from the 0 position so that the numeral 9 appears in the Nth order window 12. The counting element of the Nth order in passing from the 0 to the 9 position effects a carryover in the units order. When the carryover switch 82 of the Nth order is actuated by the cam of the counting disk, the lower terminal of the Nth order carryover capacitor 87 is connected to the positive terminal 30 of the source and the capacitor charged. The return of the switch 82 to its normal position following the passage of the cam connects the positive terminal of the capacitor to the control grid of the run tube 41 of the units order over the following circuit: Normally closed conductor 93a of the clear switch, normally closed contact 82a of the Nth

order carryover switch 82, conductor 94, normally closed contacts 93b of the clear switch, conductor 95, normally closed contacts 96a of the units order starting switch 96, conductor 97 to the control grid of the run tube 41 of the units order. On the next succeeding peak of triggering voltage which is supplied from the oscillator 62 to the shield grid of the run valve, the run valve is fired and the unit counting disk is rotated 36 degrees in the reverse direction from the 0 position so that the numeral 9 appears in the units order window. As the units order disk passes from the 0 to the 9 position the units order carryover switch 79 is actuated to effect a carryover of 1 in the tens order. This results in rotating the tens order actuating disk 7, 36 degrees in the reverse direction.

In response to the depression of the 2 amount key in the tens order, the counting disk 7 is rotated 72 degrees in the reverse direction so that the digit numeral 2 appears in the window. Finally, in response to the depression of the amount key 4 in the units order the counting disk is rotated another 144 degrees in the reverse direction so that the numeral 5 appears in the units order counting window. Thus, in the units window the digit numeral 5 appears. In the tens order the digit numeral 2 appears, and in the hundreds order window the digit numeral 9 appears. In the next higher order window and in all succeeding windows up to the Nth order window the digit numeral 9 appears. If the machine is a 9 column machine the amount 999,999,925 will appear in the windows. This amount is recognized by accounting machine operators as the true 9's complement of the negative amount 74 which is the difference between 150 plus and 224 minus. If the correct negative total is desired at this point in the calculations, it is obtained by subtracting the amount 999,999,925 from the amount 999,999,999 which is the negative equivalent of zero. In performing this subtraction the answer 74 is obtained. However, if there are further addition item entries, the total is not taken at this point. By operating the switch 22 to connect the motor 19 to the source for rotation in the positive direction, further additions may be made and the correct positive amount will appear in the windows if the additions total more than 74. For example, assume that the 9's complement negative balance which appears in the windows is 9 in the Nth order, 9 in the hundreds order, 2 in the tens order, and 5 in the units order, and that it is desired to add the positive amount 224. The operator depresses the amount key 2 in the hundreds order, the amount key 2 in the tens order, and the amount key 4 in the units order. In response to the depression of the amount key 2 in the hundreds order, the counting disk in the hundreds order is advanced 72 degrees in the positive direction so that the numeral 1 appears in the hundreds order window. In passing from the 9 to 0 position the hundreds order carryover switch 81 is actuated to effect a carryover of 1 into the next higher order which in this case is assumed to be the Nth order. Consequently, the counting disk of the Nth order is advanced 36 degrees from the 9 position to the 0 position so that the numeral 0 appears in the Nth order window. The Nth order counting disk in passing from the 9 to the 0 position effects a carryover of 1 into the units order as a result of which the units order counting disk 6 is advanced 36 degrees in the positive direction so that the numeral 6 appears in the units order

window. In response to the depression of the amount key 2 in the tens order, the counting disk 7 of the tens order is advanced 72 degrees in the positive direction so that the numeral 4 appears in the window. Finally, in response to the depression of the amount key 4 in the units order, the units order counting disk 6 is advanced 144 degrees in the positive direction so that the numeral 0 appears in the units order counting window. As the units order counting disk passes from the 9 position to the 0 position, the units order carryover switch 79 is actuated to effect a carryover of 1 into the tens order so that the counting disk for the tens order is advanced 36 degrees from the 4 position to the 5 position and the numeral 5 appears in the tens order window. Thus, the amount showing in the window is 150 which is obviously the correct answer since the last two described calculations involved a subtraction of 224 from the amount 150 and then an addition of 224 to the balance.

If it was not possible to prevent a carryover in any order while an amount key in that order is depressed, an incorrect result would be obtained because the timing circuit for the amount key depressed and the timing circuit for the carryover count of 1 would be simultaneously connected in parallel. This would result in incorrect timing action of the circuits involved. This inadmissible result is prevented by arranging the circuits so that the lead from the carryover capacitor of each order passes through a contact of the starting switch in the next higher order. Consequently, if an amount key in any order is depressed during either a positive or negative carryover from the next lower order, the starting switch of the order in which the amount key is depressed is opened to interrupt the connection between the carryover capacitor of the next lower order and the control grid of the run valve of the order in which the amount key is depressed. This circuit cannot be completed until the depressed amount key is released and the run switch returned to its closed position. For example, if an amount key in the tens order is depressed, the run switch 54 is operated to its open position and the contacts 55a are opened. Thus, the circuit between the units order carryover capacitor 84 and the grid 27c of the run tube of the tens order is interrupted at the open switch contacts 55a.

In order to provide for clearing the accumulator, i. e. restoring the counting disks to their 0 position, a clear key 98 is provided together with clear switches 99, 89, 100 and 93 for the units, tens, hundreds and N^{th} order respectively. As shown in Fig. 2, the clear switches are mounted on the uprights in which the amount keys are supported. For example, the clear switch 89 for the tens order is mounted on the upright 48. The actuating buttons of the clear switches are actuated by cam surfaces which are secured to a rod 101 which is mounted for transverse sliding movement with respect to the supporting uprights. For example, the actuating button 89c of the clear switch 89 of the tens order is operated by means of the cam surface 101a and similarly the operating button of the units order clear switch 99 is operated by means of a cam surface 101b. The buttons of the run switches for the higher orders (not shown in Fig. 2) are operated by similar cam surfaces carried on the leftward extension of the rod 101.

The stem of the clear key 98 is provided with a pin 98a which normally rests in the slot in

the bifurcated end of the horizontal arm of a bellcrank lever 102 which is pivotally mounted on a supporting upright 103. The rod 101 is provided with a pin 104 in cooperative relationship with the vertical arm of the bellcrank lever 102. When the clear key 98 is depressed, the bellcrank lever 102 is rotated in a counterclockwise direction so that its vertical arm engages the pin 104 and moves the rod 101 to the left. The rod 101 in moving to the left depresses the actuating buttons of the clear switches.

The rod 101 is further provided with cam surfaces 105, 106, etc., one for each order. These cam surfaces effect movement of the rod 50 in the tens order and corresponding rods in the other orders which actuate the starting switches.

The manner in which the accumulator is cleared is explained by assuming that the total 150 has been recorded by the counting disks and the clear switch is depressed to clear the accumulator. In response to the depression of the clear key, the rod 101 is moved to the left. This leftward movement of the rod 101 operates the clear switches of each order but not the amount key switches. For example, in the tens order, the normally closed contacts 89a and 89b are opened and the normally open contacts 89d are closed. Corresponding contacts in the clear switches 99, 100 and 93 of the units, hundreds and N^{th} orders are operated to corresponding positions. Simultaneously, the operating rod 50 in the tens order and corresponding rods in the other orders are moved to the left by the cam surfaces carried on the rod 101, of which the cam surfaces 105 and 106 for the units and tens orders, respectively, are illustrated. The rod 50 in moving to the left opens the normally closed contacts 54a, 55a and 56a and closes the normally open contacts 56b of the starting switch of the tens order. This results in firing the run valve 27 and attracting the counting disk 7 into engagement with the rotating ring 17. Thus, the counting disk 7 is rotated in the positive direction toward its 0 position. The opening of the contacts 54a not only interrupts the connection between the timing capacitor 46 and the count of 1 timing resistor 28a but also locks out the amount keys, so that the timing circuit for controlling the valves comprises the capacitor 46 and the one megohm resistor 77 only. The time constant of this circuit is approximately $40/60$ second which is greatly in excess of the amount of time required for the counting disk to make a complete revolution.

When the counting disk 7 passes from the 9 to the 0 position, the carryover switch 80 of the tens order is operated to open its normally closed contacts 80a and close its normally open contacts 80b and subsequently to reclose its normally closed contacts 80a and open its normally open contacts 80b. In the close position of the contacts 80b, the control grid 28c of the standby valve is connected through the closed contacts 89d of the clear switch and the contacts 89b of the carryover switch to the positive terminal 30 of the direct voltage source. At this point the timing circuit comprises the capacitor 46 connected in series with the resistors 77 and 107 in parallel. The time constant of this circuit is $1/120$ second which corresponds to 18 degrees revolution of the counting disk or a count of one half. At the instant of the actuation of the carryover switch, the counting disk is 18 degrees from the 0 position. Thus, as the counting disk reaches the 0 position the voltage of

the control grid 28c reaches the critical firing value and simultaneously a pulse of triggering voltage is supplied from the oscillator 61 to the shield grid 28d, with the result that the standby tube is fired. This terminates conduction in the run valve and attracts the counting disk into engagement with the stationary ring at the 0 position of the counting disk with the numeral 0 appearing in the window. The clearing operation for the remaining orders of the accumulator is identical with the operation just described and takes place simultaneously as it is simultaneously initiated in all orders of the accumulator in response to the depression of the clear key.

Although in accordance with the provisions of the patent statutes this invention is described as embodied in concrete form and the principle thereof has been explained together with the best mode in which it is now contemplated applying that principle, it will be understood that the elements shown and described are merely illustrative and that the invention is not limited thereto since alterations and modifications will readily suggest themselves to persons skilled in the art without departing from the true spirit of this invention or from the scope of the annexed claims.

What we claim as new and desire to secure by Letters Patent of the United States, is:

1. In an accounting machine, a constant speed driving member, a stationary member, a counting element normally in engagement with said stationary member, means for controlling the alternate engagement of said counting element with said stationary member comprising electric valve means provided with a control grid, means for controlling said electric valve means comprising a plurality of resistance-reactance timing circuits connected to said grid having time constants corresponding to different digit numerals, means for selecting for timing operation a circuit corresponding to a predetermined digit numeral, and means for controlling said electric valve means to effect the engagement of said counting element with said driving member and to initiate the timing action of the selected circuit to control said valve means to effect the reengagement of said counting element with said stationary member thereby to effect an amount of movement of said counting element corresponding to said predetermined digit numeral.

2. In an accounting machine accumulator, a constant speed driving means, a stationary member, a counting element, a first electric valve for controlling the engagement of said counting element with said driving means, a second electric valve for controlling the engagement of said counting element with said stationary member, a plurality of timing circuits for controlling said valves to effect the engagement of said counting element with said driving means for periods of time corresponding to the digit numerals thereby to effect amounts of movement of said counting element corresponding to said digit numerals.

3. In an accounting machine accumulator, a rotatably mounted driving member, means for driving said member at constant speed, a stationary member mounted in spaced relationship with said driving member, a counting element of magnetic material rotatably mounted in the space between said members, a first electromagnet for attracting said counting element into engagement with said driving member, a second electromagnet for attracting said counting element into engage-

ment with said stationary member, electric valve means for alternately supplying current to the windings of said magnets, a plurality of timing circuits for controlling said valve means to excite the winding of said first electromagnet for periods of time corresponding to the digit numerals thereby to effect amounts of rotation of said counting element corresponding to said digit numerals, and means for selectively initiating the timing action of said circuits.

4. In an accounting machine accumulator, a rotatably mounted driving member, means for driving said member at constant speed, a stationary member, a counting element of magnetic material, a first electromagnet for attracting said counting element into engagement with said driving member, a second electromagnet for attracting said element into engagement with said stationary member, a normally non-conducting first electric valve for supplying current to the winding of said first electromagnet, a normally conducting electric valve for supplying current to the winding of said second electromagnet, a plurality of timing circuits for controlling the conduction of said first valve and the non-conduction of said second valve for periods of time corresponding to the digit numerals, means for selecting a timing circuit corresponding to a predetermined digit numeral, and means for initiating the conduction of said first valve and interrupting the conduction of said second valve for attracting said counting element into engagement with said driving member, and for initiating the timing action of said selected circuit to reestablish the conduction of said second valve and interrupt the conduction of said first valve thereby to effect an amount of movement of said wheel corresponding to said predetermined digit numeral.
5. In an accounting machine accumulator, a rotatably mounted driving member, means for driving said member at constant speed, a stationary member, a counting element of magnetic material, a first electromagnet for attracting said counting element into engagement with said driving member, a second electromagnet for attracting said element into engagement with said stationary member, a normally non-conducting first electric valve provided with anode, cathode and control grid for supplying current to the winding of said first electromagnet, a normally conducting second electric valve provided with anode, cathode and control grid for supplying current to the winding of said second electromagnet, a plurality of timing circuits connected to the grid of said second valve for controlling the conduction of said first valve and the non-conduction of said second valve for periods corresponding to the digit numerals, means for selecting a timing circuit corresponding to a predetermined digit numeral, and means for initiating conduction of said first valve and interrupting the conduction of said second valve to attract said element into engagement with said driving member and for initiating the timing action of said selected circuit to control said valves to attract said element into engagement with said stationary member thereby to effect an amount of movement of said element corresponding to said predetermined digit numeral.
6. In an accounting machine accumulator, a rotatably mounted driving member, a stationary member mounted in spaced relationship with said driving member, a counting element rotatably mounted in the space between said driving and

stationary members, each of said members and said element having a plurality of relatively high and low portions constituting interengaging members, a source of alternating voltage, a synchronous motor supplied from said source for rotating said driving member, electric valve means for controlling the alternate engagement of said counting element with said driving member and stationary member, a plurality of timing circuits for controlling said valve means to effect engagement of said counting element with said driving member for periods of time corresponding to the digit numerals, and means for controlling said valve means to effect engagement of said counting element with said driving member at a predetermined instant in the alternating voltage wave of said source.

7. In an accounting machine, a rotatably mounted driving member, a stationary member mounted in spaced relationship with said driving member, a counting element of magnetic material rotatably mounted in the space between said driving and stationary members, each of said members and said wheel being provided with a plurality of relatively high and low portions constituting interengaging members, a source of alternating voltage, a synchronous motor supplied from said source for rotating said driving member, a first electromagnet for attracting said counting element into engagement with said driving member, a second electromagnet for attracting said counting element into engagement with said stationary member, electric valve means for alternately supplying exciting current to the windings of said electromagnets, a plurality of timing circuits for controlling said valve means to excite the winding of said first electromagnet for periods of time corresponding to the digit numerals, and means for controlling said valve means to initiate the excitation of the winding of said first electromagnet at a predetermined instant in the alternating voltage wave of said source.

8. In an accounting machine accumulator, a constant speed driving means, a stationary member, a counting element of magnetic material, a first electromagnet for attracting said counting element into engagement with said driving means, a second electromagnet for attracting said element into engagement with said stationary member, a normally non-conducting first electric valve provided with anode, cathode and control grid for supplying current to the winding of said first electromagnet, a normally conducting second electric valve provided with anode, cathode and control grid for supplying current to the winding of said second electromagnet, means for interrupting conduction of either of said valves in response to initiation of conduction of the other of said valves, a plurality of timing circuits connected to the grid of said second valve for controlling the conduction of said first valve and the non-conduction of said second valve for periods of time corresponding to the digit numerals, means for selecting a timing circuit corresponding to a predetermined digit numeral, means for applying a voltage to one of said grids to prepare said valve means for conduction and an electric valve oscillator excited from said source for supplying periodic voltage impulses to the other of said grids to initiate conduction of said valve means and the timing action of said selected circuit at a predetermined instant in the alternating voltage wave of said source.

9. In an accounting machine accumulator, a

constant speed driving means, a stationary member, a counting element of magnetic material, a first electromagnet for attracting said counting element into engagement with said driving means, a second electromagnet for attracting said element into engagement with said stationary member, a normally non-conducting first electric valve provided with anode, cathode and control grid for supplying current to the winding of said first electromagnet, a normally conducting second electric valve provided with anode, cathode and control grid for supplying current to the winding of said second electromagnet, means for interrupting conduction of either of said valves in response to initiation of conduction of the other of said valves comprising a capacitor connected between said anodes, a plurality of resistance reactance timing circuits each having a time constant proportional to a different digit numeral connected to the grid of said second valve for controlling the conduction of said first valve and the non-conduction of said second valve for periods of time corresponding to said digit numerals, means for selecting a timing circuit corresponding to a predetermined digit numeral, a normally charged capacitor and means for applying the charge of said capacitor to the grid of said first valve to initiate conduction to attract said counting element into engagement with said driving member and to initiate the timing action of said selected circuit to attract said counting element into engagement with said stationary member thereby to effect an amount of rotation of said counting element corresponding to said predetermined digit numerals.

10. In an accounting machine, a driving member, a stationary member, a counting element, a source of alternating voltage, a synchronous motor supplied from said source for rotating said driving member at constant speed, means for controlling the alternate engagement of said counting element with said driving member and said stationary member comprising electric valve means provided with a pair of control grids, means normally biasing both said grids below the critical firing value, a plurality of timing circuits for controlling said valve means for periods of time corresponding to the digit numerals, means for selecting a timing circuit corresponding to a predetermined digit numeral, means for applying a voltage to one of said grids to prepare said valve means for conduction and an electric valve oscillator excited from said source for supplying periodic voltage impulses to the other of said grids to initiate conduction of said valve means and the timing action of said selected circuit at a predetermined instant in the alternating voltage wave of said source.

11. In an accounting machine, a substantially constant speed driving means, stationary holding means, a plurality of successive ordinal counting elements normally in engagement with said holding means, a plurality of separate electric valve means, one for each of said counting elements for controlling the alternate engagement of each of said elements with said holding means and said driving means, a plurality of resistance reactance timing circuits operatively associated with each of said valve means for controlling the associated valve means to effect engagement of the associated counting element with said driving means for periods of time corresponding to the digit numerals thereby to effect amounts of movement of said counting element corresponding to the digit numerals, and means for controlling said

valve means to effect carry-overs from one order to the next.

12. In an accounting machine, a substantially constant speed driving means, a stationary holding means, a plurality of successive ordinal counting elements normally in engagement with said holding means, a plurality of separate electric valve means, one for each of said counting elements for controlling the alternate engagement of each of said elements with said holding means and said driving means, a plurality of resistance reactance timing circuits operatively associated with each of said valve means for controlling the associated valve means to effect engagement of the associated counting element with said driving means for periods of time corresponding to the digit numerals thereby to effect amounts of movement of said counting element corresponding to the digit numerals, and means for controlling said valve means to effect the engagement of said elements with said driving means and to initiate the timing action of the timing circuit associated with the count of 1 of each order for effecting carry-overs from one order to the next.

13. In an accounting machine, a substantially constant speed driving means, a stationary holding means, a plurality of successive ordinal counting elements normally in engagement with said holding means, a plurality of separate electric valve means, one for each of said counting elements for controlling the alternate engagement of each of said elements with said holding means and said driving means, a plurality of resistance reactance timing circuits operatively associated with each of said valve means for controlling the associated valve means to effect engagement of the associated counting element with said driving means for periods of time corresponding to the digit numerals thereby to effect amounts of movement of said counting element corresponding to the digit numerals, means actuated by each of said elements in a predetermined position thereof for effecting carry-overs from each order to the next, and electrically controlled means associated with the lowest order and controlled by the highest order in a predetermined position thereof to cause the ordinal counting element of the lowest order to advance one numerical position to provide for the "fugitive one."

14. In an accounting machine, a constant speed driving means, a stationary holding means, a plurality of ordinal sections each comprising an ordinal counting element normally in engagement with said holding means, a first electromagnet for attracting said counting element into engagement with said driving means, a second electromagnet for attracting said element into engagement with said holding means, an electric valve means for alternately supplying current to the windings of said magnets, a plurality of timing circuits for said valve means for controlling said valve means to excite the winding of said first electromagnet for periods of time corresponding to the digit numerals, means for selecting timing circuits corresponding to predetermined digit numerals, means for controlling said valve means to initiate engagement of said counting element with said driving means and to initiate the timing action of said selected circuit to control said valve means to effect reengagement of said element with said holding means thereby to effect an amount of rotation of said element corresponding to said predetermined digit numerals, and means for controlling said valve means to effect carry-overs from one order to the next.

15. In an accounting machine, a constant speed driving means, a stationary holding means, a plurality of ordinal sections each comprising an ordinal counting element normally in engagement with said holding means, a first electromagnet for attracting said counting element into engagement with said driving means, a second electromagnet for attracting said element into engagement with said holding means, an electric valve means for alternately supplying current to the windings of said magnets, a plurality of timing circuits for said valve means for controlling said valve means to excite the winding of said first electromagnet for periods of time corresponding to the digit numerals, means for selecting timing circuits corresponding to predetermined digit numerals, means for controlling said valve means to initiate engagement of said counting element with said driving means and to initiate the timing action of said selected circuit to control said valve means to effect reengagement of said element with said holding means thereby to effect amounts of rotation of said element corresponding to said predetermined digit numerals, and means for controlling said valve means to effect the engagement of said counting element with said driving means and to initiate the timing action of the timing circuit associated with the count of 1 of each order for effecting carry-overs from one order to the next.

16. In an accounting machine, a constant speed driving means, a stationary holding means, a plurality of ordinal sections each comprising a counting element normally in engagement with said holding means, means for controlling the alternate engagement of said counting element with said driving means and said holding means comprising electric valve apparatus provided with a control grid, a plurality of resistance reactance timing circuits connected to said grid for controlling said valve means to effect engagement of said counting element with said driving means for periods of time corresponding to the digit numerals, and means for effecting carry-overs from one order to the next comprising a capacitor for each of said sections, and means controlled by the next lower order for connecting said capacitor to said grid thereby to control said valve means to initiate engagement of said counting element with said driving means and to initiate the timing action of the timing circuit associated with the count of 1.

17. In an accounting machine, a constant speed driving means, a stationary holding means, a plurality of ordinal sections each comprising a counting element normally in engagement with said holding means, means for controlling the alternate engagement of said counting element with said driving means and said holding means comprising electric valve apparatus provided with a control grid, a plurality of timing circuits connected to said grid for controlling said valve means to effect engagement of said counting element with said driving means for periods of time corresponding to the digit numerals, and means for effecting carry-overs from one order to the next comprising a capacitor for each of said sections, means actuated by the counting element of the next lower order in a predetermined position thereof for connecting said capacitor to said grid thereby to control said valve means to initiate engagement of said counter element with said driving means and to initiate the timing action of the circuit associated with the count of 1, and switching means interlocked with said

counting elements for interrupting said capacitor connections during a counting operation thereby to prevent carry-overs during counting operations.

18. In an accounting machine, a constant speed driving means, a stationary holding means, a plurality of ordinal sections each comprising a counting element normally in engagement with said holding means, electric valve means for controlling the alternate engagement of said counting element with said holding means and said driving means, and a plurality of resistance reactance timing circuits for controlling said valve means to effect engagement of said counting element with said driving means for periods of time corresponding to the digit numerals thereby to effect amounts of movement of said counting element corresponding to said digit numerals, means for reversing the direction of rotation of said driving means to provide for subtracting operation, means for controlling said valve means for effecting carry-overs from one order to the next higher order, and means associated with the lowest order and controlled by the highest order to cause the counting element of the lowest order to advance one numerical position to provide for the "fugitive one."

19. In an accounting machine, a constant speed driving means, a stationary holding means, a plurality of ordinal sections each comprising a counting element normally in engagement with said holding means, means for controlling the alternate engagement of said counting element with said driving means and said holding means comprising electric valve apparatus provided with a control grid, a plurality of timing circuits connected to said grid for controlling said valve means to control the engagement of said counting element with said driving means for periods corresponding to the digit numerals, and means for effecting carry-overs from one order to the next comprising a separate capacitor for each of said sections, means for charging said capacitor, and means actuated by said counting element of each order for connecting the associated capacitor to the grid of the valve means of the next higher order thereby to control said valve means to initiate engagement of the associated counting element with said driving means and to initiate the timing action of the count of 1 timing circuit associated with said valve means.

20. In an accounting machine accumulator, a constant speed driving means, a stationary member, a plurality of ordinal sections each comprising a counting element, an electric valve means for controlling the alternate engagement of said

counting element with said driving means and said stationary element, and a plurality of resistance reactance timing circuits for controlling said valve means to effect engagement of said counting element with said driving means for periods of time corresponding to the digit numerals thereby to effect amounts of movement of said counting element corresponding to said digit numerals, and means for reversing the direction of rotation of said driving means to provide for subtracting operation.

21. In an accounting machine accumulator, a constant speed driving means, a stationary member, a plurality of ordinal sections each comprising a counting element, an electric valve means for controlling the alternate engagement of said counting element with said driving means and said stationary element, and a plurality of resistance reactance timing circuits for controlling said valve means to effect engagement of said counting element with said driving means for periods of time corresponding to the digit numerals thereby to effect amounts of movement of said counting element corresponding to said digit numerals, means for controlling said valve means to effect carry-overs from one order to the next, means for reversing the direction of rotation of said driving means to provide for subtracting operation, and means associated with the lowest order in the accumulator and controlled by the highest order in passing from the "9" to the "0" position to cause the lowest order to advance one numerical position to provide for the "fugitive one."

CHARLES J. GOODALE.
